(57) **CLAIM**

The ornamental design for a combined ironing board, electric iron, and iron holder, substantially as shown and described.

DESCRIPTION

FIG. 1 is a top and side perspective view of a combined ironing board, electric iron, and iron holder, with a second electric cord being partially shown for ease of illustration; FIG. 2 is a top and side perspective view thereof, with the second electric cord omitted for ease of illustration; FIG. 3 is a side elevational view thereof, showing the ironing board partially closed and the iron in a first, partially stored position with the vertical cord support, iron holding tray and second electric cord omitted for ease of illustration; FIG. 4 is side elevational view of FIG. 3 showing the ironing board completely closed and the second electric cord in a stored position;

FIG. 5 is an enlarged, fragmentary, top perspective view of the ironing board;

FIG. 6 is an enlarged, fragmentary, top perspective view of FIG. 1, with the iron placed on the ironing board;

FIG. 7 is an enlarged, fragmentary, bottom perspective view showing the components in a completely stored position;

FIG. 8 is a top and side perspective view of FIG. 2, with the iron shown in a second partially stored position and the vertical cord support and iron holder being omitted for ease of illustration;

FIG. 9 is a top and side perspective view of FIG. 8, with the ironing board partially closed; and,

FIG. 10 is a side elevational view of FIG. 4, with the iron in a completely stored position and the vertical cord holder and the iron holder omitted for ease of illustration.
